FINE MESH SCREEN BOX

Edward C. Berghoefer, Los Angeles, Calif., assignor to Link-Belt Company, Chicago, Ill., a corporation of Illinois

Application May 29, 1931. Serial No. 540,859

3 Claims. (Cl. 209—403)

This invention relates to improvements in vibrating screen boxes, particularly with regard to the method of supporting the screen.

The general object of this invention is to provide an improved screen box structure in which fine mesh screen cloth is supported and secured in place in a manner to insure a minimum wear on the screen cloth with the resultant increase in its life.

10 Within the general object of the invention it is a purpose to employ resilient contact or supporting members between the screen cloth and the transverse supports of the screen box.

A still further object of this invention is to 15 employ tubular rubber members against which the screen cloth contacts.

Another object of this invention involves the use of such a contact member for the purpose of preventing the liquid following along the 20 undersurface of the cloth when wet materials are being screened.

These and many other objects as will appear from the following detail disclosure are secured by means of this invention.

25 This invention resides substantially in the combination, construction, arrangement and relative location of parts, all as will be set forth in greater detail hereinafter.

Referring to the drawing:

30 Fig. 1 is a perspective view of a part of the screen box with some of the parts broken away showing the invention applied thereto;

Fig. 2 is a cross sectional view taken on the line 2—2 of Fig. 1.

35 The life of fine mesh screen cloth having, for example, 30 meshes to the inch and finer, is a relatively short life when used in vibrating screen boxes. Such a cloth is rather delicate in structure, and as a result has a tendency to 40 rapidly wear away at the points of contact between it and portions of the screen box. This wear occurs particularly at the points where the screen cloth contacts with the transverse members of the screen box which extend underneath 45 the cloth and support it at spaced intervals.

The structure of this invention involves the use 50 of a cushioning member, and more particularly members of rubber which are mounted between the screen and the transverse supporting members. By means of this structure it has been found by actual experience that the life of the cloth is materially lengthened. In addition when wet materials are being screened such as 55 for example the so-called "rotary mud", these cushioning members act as wipers to remove the

water which runs along the undersurface of the screen.

These and other advantages will appear from the following detail disclosure.

Referring to the drawing a portion of a screen 60 box is illustrated therein. It may be pointed out that the particular construction of the screen box itself is not by itself a particular feature of this invention. It will be apparent from the following disclosure that the invention may be 65 applied to all types of screen boxes. The important feature is that the resilient members be mounted between the screen cloth itself and the bars or members of the screen box which are normally provided in all types of screen box 70 construction for supporting the cloth at spaced intervals. The screen box itself is shown comprising side channel irons 1, of which two are usually employed running parallel to each other and longitudinally of the box to form the sides 75 thereof. These side channels 1 are united by transverse bars 2, which are shown in the form of angle irons in the illustration. The side members and transverse members are united in any suitable manner, as by bolts, welding, and the 80 like. Extending along the inner face of each of the side channels 1 are movable channel members comprising the inclined wall 3 and the substantially right angled flanges 4 and 5, all of which are formed from a single plate. These 85 channels, which may be termed cloth tensioning channels are supported adjacent the side channels so that the upper flange 4 fulcrums against the vertical wall of the side channels. The tensioning channels may be moved about their ful- 90 crum and drawn towards the side channels by means of a series of bolts 6 which extend through them and the side channels and coop- 95 erate with wing nuts 7.

Each transverse bar 2 is provided with a hole 95 8 adjacent each side channel in transverse alignment. A tube of soft rubber 18 is laid upon each transverse member 2 with its ends 9 pulled down through the hole 8. The hole 8 is slightly smaller in diameter than the external diameter of 100 the tube 18 so that when the ends are forced into the holes 8 the tubes are clearly held in place as is indicated in Fig. 2. The tubes are restricted at the point of passage through the hole 8 in the region indicated by the reference 105 numeral 10. This effects the securing action described.

The screen cloth is shown at 11, having its side edges clamped between two channel irons 12 and 13 which are clamped together at spaced 110

intervals by means of the nuts and bolts 14. The flange 5 and the tensioning channel engages with the channel 13 as indicated, so that as the wing nuts 7 are drawn up the tensioning channels swing towards the side channels to stretch the screen cloth 11 transversely.

It should be noted that no means is shown for tensioning the cloth longitudinally. It is not the usual practice to tension the cloth longitudinally, but of course this may be done without departing from the scope of this invention. Although not shown, it is usual to provide a bar extending longitudinally and centrally of the cloth to which the cloth is secured. This bar tends to prevent wiping and is usually clamped down to the screen frame so that the cloth is secured longitudinally along its center line.

By this construction it will be seen that when the screen is in action any relative movement between the cloth and the transverse members 2 does not cause wearing of the cloth because of the fact that the tubular members are interposed between the cloth and the transverse members. By means of this construction it has been found that the life of fine mesh screens is materially lengthened. When wet materials are being scanned such as for example what is known as "rotary mud", which is produced from the drilling of oil wells, the resilient members also act as wipers, causing the liquid to run off the undersurface of the screen and prevent it from following along the undersurface of the screen.

The fact that the cushioning members 18 are tubular is of considerable importance. Experience has shown that solid rubber cushioning members do not materially increase the life of the screen. The tubular member, however, appears to effect less wearing action on the cloth, so that its life is materially lengthened.

It is emphasized that although the circular form of tube is preferable, hollow resilient tubes of other cross sectional forms may be used to advantage.

From the foregoing description it will be apparent that this invention resides in certain principles of construction and operation, which of course may be embodied by those skilled in the art in other physical forms, and I do not therefore desire to be limited to the disclosure which has been given in an illustrative sense, but rather to the scope of the appended claims.

What I seek to secure by United States Letters Patent is:

1. A screen box of the type described comprising a frame made up of longitudinal and transverse members having apertures therein, flexible tubular members having their ends secured in the aperture so as to rest upon the transverse members and a screen cloth secured to the frame and resting on the flexible tubular members.

2. A screen box of the type described comprising a frame made up of side and transverse bottom members secured together, said transverse bottom members having a hole therein ad-

jaacent each side member, a resilient tubular member overlying each transverse member with its ends inserted in the holes, a screen cloth resting on the tubular members, and means for tensioning the screen cloth.

3. A screen box of the type described comprising a frame made up of side and transverse bottom members secured together, said transverse bottom members having a hole therein adjacent each side member, a resilient tubular member overlying each transverse member with its ends inserted in the holes, a screen cloth resting on the tubular members, and means for tensioning the screen cloth longitudinally, said holes being of a smaller diameter than the tubular members so as to frictionally secure them in place.

4. In a device as described the combination consisting of a screen box having transverse structural members, a screen cloth secured in said box and resilient tubular members interposed between the screen cloth and transverse structural members in contact therewith, upon which the screen cloth rests, the longitudinal axes of the tubular members lying parallel to the plane of the screen cloth.

5. In a vibrating screen structure the combination including a screen box having at least one transverse bar, a screen cloth extending between the sides of the box above the bar and at least one soft resilient tubular member secured between the cloth and the bar upon which the cloth rests throughout the length of the tubular member in tangential relation thereto, the tubular member collapsing and reforming with the movement of the screen when loaded.

6. In apparatus as described a screen support including side members connected by cross bars to form an open bottom frame, a screen cloth positioned above the cross bars, soft resilient hollow members interposed between the cloth and bars so as to contact tangentially throughout the length thereof, and means for securing the cloth and hollow members in the frame in contact with each other, the loaded screen in movement causes the tubular members to collapse and reform so as to maintain contact with the moving screen.

7. In a construction of the type described the combination comprising a frame made up of united longitudinal and transverse members, a screen cloth, means for securing the cloth in said frame to form a screening bottom therefor, and a plurality of soft resilient hollow members interposed between the transverse members and the cloth and extending substantially transversely of the frame in contact with each other.

8. A screen box having side members united by transverse members, a screen cloth overlying the transverse member, at least one resilient tubular member interposed between the cloth and at least one of the transverse members, and clamping means for securing the cloth in the box and for clamping the resilient member against the transverse member, whereby the cloth and resilient member are held in contact, the cloth and tubular member being in tangential contact.

EDWARD C. BERGHOEFER.
